UNITED STATES PATENT OFFICE

ERNEST B. JONES, OF SOUTH WEYMOUTH, MASSACHUSETTS, ASSIGNOR TO NATIONAL FIREWORKS, INC., OF WEST HANOVER, MASSACHUSETTS, A CORPORATION OF MASSACHUSETTS

RELEASE FOR AERIAL FLARES

Application filed February 19, 1932. Serial No. 593,963.

This invention relates to improvements in means for releasably supporting aerial flares upon aircraft. Inasmuch as flares are used to supply illumination in cases of emergency as for instance when the aircraft is forced to make a landing in unfamiliar territory, or upon an airport not provided with illumination, the means for releasing the flare should be instantly ready for use at all times. During the course of the flight of an airplane or aircraft of any type they are very commonly subject to low temperatures and sudden and unusual changes in atmospheric conditions. Such sudden changes frequently cause condensation upon all parts of the aircraft. The moisture thus accumulated often becomes frozen and in many cases a heavy accumulation of ice results. If the releasing mechanism for the flare is exposed to such conditions it may become frozen and thereby rendered inoperative.

The object of the present invention is to provide a releasing device for aerial flares which is proof against becoming inoperative by reason of atmospheric conditions.

The object of the invention is further to provide a releasing device which is normally positively locked against accidental release.

A further object of the invention is to provide a releasing device which will symmetrically support the weight of the flare from a plurality of points and release the flare at all such points simultaneously.

A further object of the invention is to provide a releasable supporting device which functions by its own locking movement positively to clamp a plurality of supporting dogs in locked position and after releasing the flare acts positively to maintain the dogs in retracted position.

Other objects and features of the invention will more fully appear from the following description in connection with the accompanying drawing and will be particularly pointed out in the claims.

The invention comprises essentially a tube closed at its topmost end and secured to the aircraft preferably in a vertical position. This tube serves to house the flare until the emergency arrives requiring its use. The

lower end of the tube desirably is substantially hermetically closed by means of a thin sheet of frangible material, thereby completely protecting the flare and the inner surfaces of the tube from accumulation of ice. The character of the frangible material at the base of the tube is such that the flare when released will penetrate without being substantially impeded.

The flare itself is similar in construction to that disclosed in U. S. Patent No. 1,755,389, granted to George J. J. Clark and Ernest B. Jones as co-inventors. The particular flare employed in the present invention desirably is provided with a peripheral shoulder near its upper end and is of such dimensions as to be freely slideable within the housing tube. The supporting parachute associated with the flare is packed in the usual manner within the upper end of the tube, while the flare itself is supported in the lower portion thereof.

The releasable supporting mechanism for the flare comprises a frame member of generally annular form surrounding and fixed to the outer periphery of the tube and has slidably mounted therein a plurality of flare supporting dogs, the inner ends of which are permitted to project through the wall of the tube and engage the shoulder upon the flare, and by such engagement support the flare within its housing tube. Associated with the dogs is a ring rotatable about the tube and having a plurality of cam slots therein corresponding in number to the number of supporting dogs. The supporting dogs are preferably uniformly spaced about the periphery of the tube and move in a plane substantially perpendicular to the axis thereof. Each dog is provided with a pin projecting upwardly into its cam slot in the ring. As the ring is rotated through a portion of a revolution the dogs are retracted by the action of the pins in the cam slots. Such retraction of the dogs releases the flare which falls by gravity penetrating the frangible closure at the base of the tube.

In the drawing:

Fig. 1 is a side elevation of a portion of an airplane partially broken away to show the

flare and its housing tube installed therein.

Fig. 2 is a cross sectional view of the flare-receiving tube showing the flare supported therein.

5 Fig. 3 is a cross section on line 3—3 Fig. 2.

Fig. 4 is a cross section on line 4—4 Fig. 3.

Fig. 5 is a cross section on line 5—5 Fig. 3.

In order to more clearly and accurately present the principles of the invention a 10 particular embodiment thereof will now be described. Inasmuch as the flare is particularly for use in emergencies it is desirably situated within the plane in a position to be readily released without interfering with 15 the flight of the aircraft and to interfere as little as possible with the occupants and the general equipment within the plane. As shown in Fig. 1 the housing tube 1 is situated in a vertical position directly in the 20 rear of the pilot's seat. The lower end of the tube 1 projects through the bottom wall of the fuselage 2. The tube 1 is desirably provided with a hook 3 adapted to engage a supporting bar 4 secured to the body of 25 the plane, thereby permitting removal of the tube from the aircraft. Any other desirable method may be employed to secure the tube 1 within the aircraft or upon the exterior thereof.

30 The supporting parachute 5 is packed within the upper portion of the tube 1 and connected by suitable cords or other connecting members 6 to the flare 7 which is supported within the lower portion of the tube with its lower extremity slightly above 35 the extreme lower limit of the tube. The general structure of the flare 7 follows the usual design having a casing 8 within which the magnesium composition is packed and is 40 desirably provided at its lower end with a firing mechanism 9 which may be of a construction similar to that disclosed by the U. S. Patent No. 1,755,389. The upper end of the flare 7 is desirably provided with a 45 metallic head 10 which is provided with a peripheral shoulder 11.

An annular frame 12 is secured by means of rivets or any suitable means to the peripheral face of the tube 1. The frame 12 50 has a vertical depending portion 13 and a horizontally-extending portion 14. The horizontal portion 14 is provided with a plurality of radial slots 16 within which are received a plurality of flare supporting dogs 55 17, the inner ends of which may be projected through apertures in the wall of the tube 1 to engage the shoulder 11 of the head 10 upon the flare. When the dogs are projected inwardly as shown in Figs. 2 and 3 the flare is 60 symmetrically supported thereby within the housing tube 1.

A rotatable ring 15 is situated above and in contact with the horizontal portion 14 of the frame 12. The ring 15 serves to retain the 65 dogs 17 within their slots 16 and is itself re-

tained in lateral position by means of a plurality of shouldered retaining screws 18 which have screw-threaded engagement with the frame 12 while their shank portions 19 are received in concentric grooves 20 formed in the ring which permit the ring 15 to rotate for a portion of a revolution.

70 The ring 15 is also provided with a plurality of cam slots 21 of a number equivalent to the number of dogs 17 and situated in a position to receive the upper end of a plurality of pins 22 fixed at their lower ends in the dogs 17. The cam slots 21 are so disposed as to move the dogs 17 from their locking position shown in Figs. 2 and 3 into their retracted position through the medium of the upwardly-extending pins 22 which are acted upon by the cam slots. The ring 15 is provided with a suitable outwardly projecting actuating arm 23 to which is secured one end of a lanyard 24. Desirably a locking means is provided to prevent accidental movement of the ring 15 and thereby unintentionally releasing the flare. Any desirable means for this purpose may be employed. A simple and effective means for 80 accomplishing this result is shown herein comprising a cotter pin 25 which projects through suitable apertures in the ring 15 and the frame 12. Such apertures are so positioned that they are in alignment when the 85 ring 15 is in its locked position. The upper end of the locking pin 25 is provided with an eye 26 within which the lanyard 24 is secured at a point removed from its point of attachment with the arm 23.

90 The moving parts of the mechanism are protected against the accumulation of ice caused by atmospheric conditions by means of a suitable cover plate 27, which desirably extends over the upper surface of the 95 ring 15, and downwardly over the outer edge of the ring and the outer edge of the horizontal portion 14 of the frame 12, thereby excluding moisture from the cam slots 21 and 100 also the grooves 16 in which the dogs 17 move. It will be observed, therefore, that the cover plate 27 renders the mechanism impervious to atmospheric conditions and insures that the flare may be instantly released in case of 105 emergency at all times.

110 The mechanism of the present invention is highly efficient and dependable in operation. As already pointed out, the moving parts of the mechanism and their paths of movement are entirely protected against an accumulation of ice, and furthermore the protecting means renders it impossible for foreign matter to obstruct the proper function of the device.

115 While it is vitally important to be able to release the flare immediately and at all events, it is also important that the releasable supporting mechanism continue to rigidly support the flare within its housing tube until an emergency arises. In the present invention 120

tion not only is there provided a locking pin acting to prevent movement of the ring 15 as above described, but the character of the locking mechanism itself constitutes an efficient means to prevent premature or accidental release of the flare. When the locking dogs 17 are in their locked position, they are automatically withheld against any retracting movement until the ring 15 is positively manually actuated. If, therefore, the locking pin 25 becomes ineffective or accidentally removed, the supporting dogs will still be held in place by the wedging action of the cam slots 20 acting upon the pins 22. If the locking pin is not in place, the dogs will positively remain in locked position and continue firmly to resist the forces of side play and the tendency towards vertical movement imposed upon the flare by landing and maneuvering of the aircraft while in the air.

It is also important to insure that the locking dogs 17 will remain in their released position after the flare has been released from its housing tube. If the ring 15 should be moved accidentally slightly in the opposite direction after being moved to release the flare, the dogs 17 would project slightly into the tube and endanger the parachute as it is drawn out of the tube by the downward movement of the flare. To prevent such an occurrence means are provided desirably to lock the ring 15 in its releasing position. Any suitable means may be employed to accomplish this end. A desirable construction is illustrated wherein a spring wire 28 is used as a locking means. The wire is looped near its central portion to provide sufficient resiliency. One end of the spring passes through the upper extremity of the reenforcing rib 29 of the frame 12 and is bent upwardly at 30 and anchored to the wall of the boss 31 within which the dogs 17 are slidably mounted. The other end of the spring 28 also is bent upwardly at 32 and is received in an aperture 33 in the horizontal portion 14 of the frame 12.

When the ring 15 is in position to support the flare the upturned end 32 of the spring bears against the lower face of the ring 15. When, however, the ring is moved into its releasing position the end 32 of the spring enters the end of the adjacent concentric slot 20 of the ring 15 and engages the wall or shoulder at the end of the slot as shown in dotted lines in Fig. 3 and in full lines in Fig. 5. The ring 15 thereby is locked in its releasing position until the end of the spring is manually withdrawn from the slot 20. Since the ring acts to retract the dogs, the dogs are positively locked against any inward motion after the flare has been discharged. The locking wire serves also as a convenient means for withholding the dogs in retracted position while packing the parachute within

its protecting tube and replacing a flare therein.

Having thus described the invention, what is claimed as new, and desired to be secured by Letters Patent, is:

1. An aerial flare releasing apparatus for air craft comprising a flare supporting tube secured upon the air craft having a closed upper end, a flare slidably mounted in the tube, an annular frame fixed upon the peripheral surface of said tube, a plurality of locking dogs slidably mounted within said frame and movable through the wall of said tube to engage and support said flare within said tube, and means to withdraw said dogs from engagement with said flare thereby releasing the flare which falls by gravity out of the lower end of said tube. 75

2. An aerial flare releasing apparatus for air craft comprising a flare receiving tube secured upon the air craft having a closed upper end, a flare within the tube, a peripheral shoulder on said flare, a plurality of locking dogs slidably mounted in said tube which move in a plane at right angles to the axis of said tube, said dogs normally projecting into said tube and engaging said shoulder and means to withdraw said dogs from said shoulder thereby releasing said flare. 85

3. An aerial flare releasing apparatus for air craft comprising a flare receiving tube fixed upon the air craft having a closed upper end and a lower end substantially hermetically sealed by a thin sheet of frangible material, a flare slidable within said tube, a plurality of locking dogs slidably mounted in said tube to move in plane at right angles to the axis of said tube normally acting to support said flare within said tube, means acting to withdraw said dogs simultaneously from engagement with said flare thereby releasing the flare which punctures the frangible sheet at the lower end of the tube and thereby is permitted to emerge from the tube and a protective cover enclosing the exposed moving parts of the releasing mechanism thereby maintaining their path of movement free from freezing moisture. 100

4. An aerial flare releasing apparatus for air craft comprising a flare receiving tube secured to the air craft, a flare slidable within said tube, an annular frame fixed upon the peripheral face of said tube, a plurality of dogs slidably mounted in said frame movable in a plane at right angles to the axis of said tube the inner ends of said dogs normally projecting through the wall of the tube and engaging said flare to releasably support the same within the tube and cam means operable to withdraw the dogs from engagement with the flare thereby to release the same. 115

5. An aerial flare releasing apparatus for air craft comprising a flare receiving tube fixed substantially vertically within the air 130

- craft, a flare slidable within said tube, an annular frame fixed to the peripheral face of said tube, a plurality of dogs slidably mounted in said frame to move in a plane at right angles to the axis of said tube, the inner ends thereof normally projecting through the tube and engaging said flare to support the same within said tube, manually operable cam means acting to simultaneously withdraw said dogs from engagement with said flare thereby releasing the same, a protecting cover enclosing the movable elements of the releasing mechanism to maintain their path of movement free from freezing moisture and a disk of frangible material acting to substantially hermetically seal the bottom end of said tube.
6. An aerial flare releasing apparatus for air craft comprising a flare receiving tube fixed upon the air craft, a flare slidable within the tube, a peripheral shoulder on said flare, an annular supporting frame fixed to the peripheral face of said tube, a plurality of radially movable dogs slidably mounted in said frame, the inner ends thereof normally projecting through the walls of said tube to engage the shoulder on said flare thereby supporting the same within the tube, a ring rotatable upon the periphery of said tube adjacent to said annular frame, cam surfaces upon said ring operable, upon rotation thereof to retract the dogs thereby releasing the flare.
7. An aerial flare releasing apparatus for air craft comprising a flare supporting tube fixed to the air craft, a flare slidable within the tube, a peripheral shoulder on said flare, an annular frame fixed upon the peripheral face of said tube, a plurality of dogs slidably mounted in said frame to move radially through the walls of said tube and normally engaging said shoulder upon said flare thereby supporting the flare within the tube, a ring rotatable upon the periphery of said tube adjacent to said frame, cam slots in said ring, cam followers secured to said dogs and projecting into said slots operable upon rotation of said ring to simultaneously retract said dogs out of engagement with said shoulder thereby to release the flare.
8. An aerial flare releasing apparatus for air craft having the elements defined in Claim 7 together with an arm projecting outwardly from said ring, a locking pin projecting through said ring and said frame acting normally to prevent rotation of said ring and a lanyard for releasing said flare connected at its extreme end to the outer end of said arm and connected at an intermediate point to said locking pin whereby when said lanyard is manually operated the locking pin is removed and the said ring is rotated to release the flare.
9. An aerial flare releasing apparatus for air craft comprising a flare-receiving tube secured to the air craft, a flare slidably mounted within said tube, an annular frame fixed upon the outer face of said tube, a plurality of dogs slidably mounted in said frame, the inner ends thereof normally projecting through the wall of said tube engaging and releasably supporting said flare within said tube, means operable to simultaneously retract said dogs from engagement with the flare and means acting to lock said dogs in retracted position.
10. An aerial flare releasing apparatus for air craft comprising a flare-receiving tube secured to the air craft, a flare slidable within said tube, an annular frame fixed upon the outer face of said tube, a plurality of dogs slidably mounted in said frame, the inner ends thereof normally projecting through the wall of the tube engaging and releasably supporting said flare within the tube, releasing means rotatably mounted on said tube, acting when rotated to retract said dogs, a locking shoulder on said releasing means, a spring wire secured to said frame at one end and yieldingingly engaging said releasing means at its other end automatically acting to lock said releasing means in its releasing position by engagement with said shoulder.
- In testimony whereof, I have signed my name to this specification.
- ERNEST B. JONES.
